US00D640321S

(12) **United States Design Patent**
Kuronuma

(10) **Patent No.:** **US D640,321 S**
(45) **Date of Patent:** **** Jun. 21, 2011**

(54) **CORRECTION TAPE DISPENSER**

(75) Inventor: **Hiromi Kuronuma**, Saitama (JP)

(73) Assignee: **Tombow Pencil Co., Ltd.**, Tokyo (JP)

(**) Term: **14 Years**

(21) Appl. No.: **29/372,172**

(22) Filed: **Oct. 25, 2010**

(30) **Foreign Application Priority Data**

Jun. 9, 2010 (JP) 2010-014182

(51) **LOC (9) Cl.** **19-02**

(52) **U.S. Cl.** **D19/69**

(58) **Field of Classification Search** D19/66, D19/67, 68, 69, 70; 156/523, 257, 540, 577; 206/411; 225/6, 25, 39, 77; 242/588, 588.1, 242/588.2, 588.3, 588.6, 5

(57) **CLAIM**

The ornamental design of a correction tape dispenser, as is shown and described.

DESCRIPTION

FIG. 1 is a top view of the correction tape dispenser of the subject invention;

FIG. 2 is a perspective view of the correction tape dispenser of the subject invention;

FIG. 3 is a front view of the correction tape dispenser of the subject invention, which is referenced to indicate transparency;

FIG. 4 is a left side view of the correction tape dispenser of the subject invention;

FIG. 5 is a right side view of the correction tape dispenser of the subject invention;

FIG. 6 is a rear view of the correction tape dispenser of the subject invention; and,

FIG. 7 is a bottom view of the correction tape dispenser of the subject invention.
